CLAIM

The ornamental design for a combined globe and satellite, as shown and described.

DESCRIPTION

FIG. 1 is a front, top and side perspective view of the combined globe and satellite showing my new design; FIG. 2 is a front elevational view thereof; FIG. 3 is a rear elevational view thereof; FIG. 4 is a side elevational view thereof, the side opposite being a mirror image of the side shown in FIG. 4; FIG. 5 is a top plan view thereof; and, FIG. 6 is a bottom plan view thereof.

FIG.1.

FIG. 4.

FIG. 3.

FIG. 2.

FIG. 6.

FIG. 5.
